United States Patent Office

Des. 183,572
Patented Sept. 23, 1958

183,572

BOOTH OR SIMILAR ARTICLE

Henry C. Keck, Pasadena, Thomas K. Hale, Glendale,
and Norman E. Roe, Fullerton, Calif., assignors to
Harrah's Club, Reno, Nev., a corporation of Nevada

Application November 25, 1957, Serial No. 48,647

Term of patent 14 years

(Cl. D13—1)

Fig. 1.

Fig. 2.

Fig. 3.

Fig. 1 is a front perspective view of a booth embodying our new design;

Fig. 2 is a rear perspective view thereof; and

Fig. 3 is a top plan view thereof.

The side of the booth not shown in the drawing is substantially like the side thereof which is shown in the right half of Fig. 1 and the left half of Fig. 2.

We claim:

The ornamental design for a booth, or similar article, substantially as shown and described.
